UNITED STATES PATENT OFFICE

ARTHUR N. ANDERSON, OF CRAFTON, PENNSYLVANIA

VOLTAGE CONTROL SYSTEM

Application filed September 2, 1927. Serial No. 217,234.

This invention relates to a system and apparatus for supplying a constant voltage output from a variable current source.

The invention is more particularly applicable for supplying a constant low voltage current from a variable high current source, and is especially useful in supplying electric scales, or other devices requiring a substantially constant low voltage current, with the necessary low voltage on which they operate from the usual 110-volt current supply line.

It is recognized that there is considerable voltage variation in commercial 110-volt lines, and that when this current is stepped down through a transformer for use with electric scales, that the operation of the scales varies according to the current variations in the supply lines. This is, of course, detrimental to the accuracy of the scales.

The present invention may be readily understood by reference to the accompanying drawing, which illustrates diagrammatically a system and apparatus for supplying a constant lower voltage from a higher voltage source.

In accordance with the present invention, there is provided a balance beam 1 mounted on a fulcrum 2 and having a coil 3 at one end thereof. This beam may be of the type commonly employed in certain electrical measuring instruments, such for instance as the well-known Kelvin balance. The coil is connected in series and disposed between upper and lower coils 4 and 5, respectively. The coils 4, 3 and 5 are connected in series, through wires 6' and 7' shunted across wires 6 and 7, which lead to the scales or other device to which the constant voltage current is applied. Wires 6 and 7 are in the secondary circuit 8 of a transformer 9 having a primary winding 10. One side of the primary 10 is directly connected with one side of the 110-volt line L' through wire 11. The other side of the primary connects through a variable resistance 12, and a movable contact 13 with the other side L of the line.

At the end of the beam 1 is a contact making element 14 which may move into contact with either an upper contact mem-

ber 15 or a lower contact member 16, depending on which direction the beam 1 is rocked. Contact member 15 is in circuit with solenoid 17, which is connected through wire 17' with one side, L, of the supply current. Contact member 16 is in circuit with solenoid 18 and the side L' of the 110-volt line. The other side, L', of the 110-volt line is connected with the contact member 14 on the beam 1 through a suitably arranged wire 19.

On the free end of the beam 1 is a counter-weight which is preferably in the form of a flexible cord or string 20 having a series of beads 21 arranged therealong. The beads 21 are preferably non-magnetic and are preferably of a moisture-resisting material, such for instance as glass. One end of this flexible counter-weight is directly connected on the end of the balance beam, while the other end of the flexible counter-weight 19 is wound over a spool or drum 22. The drum 22 can be adjusted manually to vary the effective length of the counter-weight 20—21, according to the conditions of the circuit and the output desired in the wires 6 and 7.

The solenoids 17 and 18 are provided with armatures which are connected with a pivoted beam 13', this beam being pivoted at 13'. One of the armatures is located one side of the pivot point, and one of the armatures the other side of the pivot point, and the movable contact 13 is carried on the free end of this second beam.

In the operation of the system, assume that the transformer 9 is supposed to deliver a current of four volts to the lines 6 and 7. The adjustable weight is set to hold coil 3 and balance beam 1 in the neutral position shown in the drawings when the normal voltage is flowing through the lines 6 and 7. If there is a variation in the input voltage on the lines L—L', which may be the standard 110-volt current supply lines, this variation will be instantly reflected in the lines 6 and 7. Any disturbance in the current value in lines 6 and 7 will cause the armature 3 to be moved up and down, thereby bringing contact member 14 into circuit

closing position with either contact 15 or contact 16, depending on the fluctuation of the current, thereby energizing either coil 17 or 18, as the case may be. Energization of either of the solenoids 17 or 18 will effect a movement of the beam 13' to vary the resistance 12 in the circuit of the primary winding 10 of the transformer 9.

As thus arranged, it will be seen that if there is a voltage drop in the 110-volt lines, the contact member 13 will move down, cutting out resistance in the primary circuit but if there is an increase in the supply of voltage, the lever 13' will move in the opposite direction to cut in more resistance in the primary circuit. This will tend toward maintaining a constant output voltage across lines 6 and 7.

In place of the particular flexible counter weight illustrated, any suitable counter-acting mechanism may be substituted, but a mechanism is preferably used which can be variable so that it can be readily set according to particular conditions of use, and a flexible weight such as that shown is preferred because of the fine increments of adjustment obtainable, together with the constant effect which is exerted thereby, as compared with the variable nature of the springs and similar counter-balancing devices, such as are sometimes employed.

The advantages of the present invention arise out of the fact that a simple arrangement is provided for effectively maintaining a substantially constant potential across the lines 6 and 7, whereby a current supplied from commercial lines can be effectively utilized in connection with electric weighing scales or other electrical apparatus requiring a substantially constant current for their operation.

While the apparatus disclosed is relatively simple, it is extremely responsive to small current variations, utilizing as it does, principles of the Kelvin balance, and delicate increments of adjustment can be readily obtained.

While I have diagrammatically illustrated one system embodying the invention, it will be understood that the form illustrated is merely illustrative of one embodiment, and that the invention may be otherwise embodied, and that various modifications and changes may be made within the spirit of my invention and under the scope of the following claims.

I claim:

1. A voltage regulating system including input and output circuits, a Kelvin balance in the output circuit, a rheostat in the input circuit, and means responsive to a movement of the balance for varying the rheostat, said balance having a beam, a flexible counterbalance for the beam, and means for

adjustably varying the flexible counterbalance.

2. A voltage regulating system including input and output circuits, a Kelvin balance in the output circuit, a rheostat in the input circuit, means responsive to a movement of the balance for varying the rheostat, said balance having a beam with a flexible cord attached thereto, beads on the cord to provide a counterbalance for the beam, and means for increasing or decreasing the effective length of the counterbalance.

3. An alternating current source of variable voltage, electric scales requiring a constant voltage low in magnitude as compared with the voltage of said source, means whereby a constant low voltage may be supplied to said scales by said alternating current source, including a step-down voltage transformer having its high voltage primary winding energized by said source and its secondary low voltage winding energizing said scales, a variable resistor in series circuit with the high voltage winding, a Kelvin balance across the low voltage winding, and means energized by said balance for uniformly changing the resistance of the resistor in accordance with changes in the voltage of the low voltage winding, whereby a constant low voltage is supplied to the scales.

In testimony whereof I have hereunto set my hand.
